UNITED STATES PATENT OFFICE

WILLIAM E. BIHL AND AXEL RAMCLAW, OF CHICAGO, ILLINOIS, ASSIGNORS TO ZERO-ZONE CORPORATION, OF CHICAGO, ILLINOIS, A CORPORATION OF ILLINOIS

DISPENSING MACHINE

Application filed January 22, 1930. Serial No. 422,512.

This invention relates to dispensing machines of the coin controlled type, more particularly to an improved coin chute and coin control for such machines.

5 In our copending applications, Serial No. 422,511 filed January 22, 1930, and Serial No. 422,513 filed January 22, 1930, we disclose an improved dispensing machine adapted to dispense ice cold bottled beverages. The 10 improved coin chute and control therefor, which forms the subject matter of the instant application, is applicable to machines of the type disclosed in these copending applications, as well as to other similar 15 machines.

In the dispensing machine disclosed in the copending applications, the articles to be dispensed from the machine are stored on a ramp which defines a helical path around 20 a cooling chamber, the articles standing on end in this ramp.

A pusher located on the ramp behind the last article in the machine is operated by 25 a driving mechanism of the windlass type to push or slide the articles along the ramp.

At the discharge end of the ramp, the articles slide off of the supporting rail of the ramp and onto a trap door, through which they fall into the discharge chute of the 30 machine. Normally, the driving mechanism is disconnected from the crank arm disposed on the outside of the machine so that a mischievous operation of that crank arm without depositing a coin in the coin slot 35 of the machine will not result in injury to the machine.

The coin slot of a machine of this type 40 communicates with a chute which leads down into the control mechanism so that the coin dropped into the slot falls thru the chute into the mechanism where it is effective to connect the driving mechanism to the crank arm, this connection being preferably accomplished in the manner pointed out in our 45 latter above mentioned copending application, although, in so far as the teachings of the present invention are concerned, any other preferred type of coin control can be substituted therefor.

50 A coin deposited in the coin slot of the

machine falls through the chute into the control mechanism, and, if special arrangements were not provided to prevent it, the coin so deposited would be collected by the machine even though no articles were in the 55 machine at the time. The customer would, therefore, get no return for his money and, as a result, an unfavorable or even antagonistic impression towards the machine would be lodged in the mind of the customer. 60

To prevent contingencies of this kind, we have provided as the object of our present invention a new and improved coin chute control which is operated when the last article in the ramp of the machine is discharged 65 from the machine to alter the coin chute so that any additional coins which may be deposited in the slot before the machine is recharged will be returned to the customer. 70

In the preferred embodiment of our invention, illustrated in the drawings by way of example, a push rod is operated by the pusher on the ramp when that pusher moves to discharge the last article from the machine. The movement of this rod controls 75 a cam, which in turn inserts blocking pins or rods into the chute leading to the control mechanism. This chute is provided with a lateral slot through which coins deposited in the slot of the machine are made to fall 80 when they strike these rods projecting into the coin chute. The lateral slot in the chute communicates with a return receptacle, from which the customer may recover his coin. 85

Now, to acquaint those skilled in the art with the teachings of our invention, reference is here made to the accompanying drawings in which a preferred embodiment of it is shown by way of example, and in 90 which:—

Fig. 1 is an elevational view of the front wall of a dispensing machine showing the coin chute control mechanism applied to the inside of that wall; 95

Fig. 2 is a cross sectional view of Fig. 1, taken along the line 2—2 looking in the direction of the arrows;

Fig. 3 is a cross sectional view taken along the line 3—3 of Fig. 2 and showing the 100

coin chute mechanism drawn to an enlarged scale;

Fig. 4 is a cross sectional view taken along the line 4—4 of Fig. 3;

5 Fig. 5 is a cross sectional view through the coin chute taken along the line 5—5 of Fig. 3; and

10 Fig. 6 is an enlarged view of the control mechanism shown in Figs. 1 to 5, inclusive.

15 As is pointed out in our above mentioned co-pending applications, the cabinet of the dispensing machine comprises an exterior wall 1 and an interior wall 2, and the space between the walls is filled with an insulating material 3, since the machine is designed to dispense cooled beverages.

20 The coin slot 4 comprises a plate 4 attached to the outside wall 1 of the machine, in the center of which plate and near the top 25 of it is the coin slot 5 through which coins are dropped to operate the control mechanism of the machine. An opening 6 is provided in the plate 4 below the slot 5, that opening registering with the return receptacle from which the customer recovers his coin when the machine is empty. The return receptacle 7 is a pocket-like compartment defined by the walls of the coin chute 8, the plate 4, and suitable end and bottom 30 members attached thereto.

25 Within the return receptacle 7, the coin chute 8, which leads from the slot 5 down into the control mechanism 9 of the machine, is provided with a lateral opening or slot 35 10 through which coins enter the return receptacle.

30 In the normal operation of the machine, that is, when there are articles to be dispensed in the machine, a coin deposited in the slot 5 falls through the chute 8 into the control mechanism 9, operating that mechanism to render it effective to dispense an article from the machine. The details of the operation of the control mechanism 9 45 may best be understood from the above mentioned copending application Serial No. 422,513, to which application reference is here made for those details.

40 Briefly, however, the operation of the control mechanism 9 moves the windlass 11 to pull the control cable 12 around through the machine. This control cable 12 is threaded over suitable pulleys and connected to the pusher 13 which rests upon the ramp 14 55 immediately behind the last article in the ramp. These articles 15 are shown as bottles, although obviously other suitable solid articles could be dispensed with an arrangement of this kind.

60 The operation of the control mechanism responsive to its receipt of the coin dropped through the slot 8 also operates the lever 16, which, through the lever 17, unblocks the star wheel 18 to permit the discharge of 65 an article from the machine.

To control the coin slot so that coins deposited in it after the last article in the machine has been dispensed will fall into the return receptacle rather than into the control mechanism, we have provided a rod 20 supported on the inside surface of the front wall 2 of the cabinet by the bushing 21 in such a manner that the rod 20 is free to rotate about its own axis. At the lower end of the rod 20 we have formed a hook-like member 22, the end of which is disposed in such a position that it is struck by the pusher when that pusher is moved to discharge the last article 15 from the machine. The pusher, upon striking the end 22 of the rod 20, rotates the rod about its longitudinal axis, and that motion is employed to control the coin chute.

70 On the upper end of the rod 20 we have provided a bell crank 23 which is connected by the lever 24 to the cam 25 of the coin slot control.

75 As will best be seen in Figs. 3, 4, and 6, a pair of cylindrical bushings 30 are attached to the walls of the coin chute 8, and a U-shaped control rod 31 is disposed in these bushings with one leg of the U in each bushing. The closed end of the rod 31 passes through the slot 32 in the cam 25, and is held therein by the slot 33 disposed in the cam slide 34 in which the cam 25 is nested.

80 Normally, the bar 31 rests in the high portion 37 of the cam, in which position the ends 35 and 36 of the bar 31 do not reach into the interior of the chute 8.

85 When the rod 20 is rotated and the bell crank and lever controlled thereby moved to slide the cam 25 in its support 34, the closed end of the U-bar 31 is moved off of the high portion 37 of the cam 25 down into the low portion 38. This movement slides the legs of the bar 31 through the bushings 30 so that the ends 35 and 36 are moved into and across the opening in the coin chute 8.

90 As will be best seen in Fig. 5, when the ends 35 and 36 obstruct the coin chute 8, a coin dropped through the slot 5, strikes the bar 35 and is deflected to the side through the opening 10 in the side of the coin chute. As the coin falls, it strikes the end 36 which further deflects it sidewise, so that the coin is discharged from the chute 8 through the opening 10 into the return receptacle 7, from which it is recovered by the customer.

95 As long as the machine remains empty and the pusher 13 bears against the end 22 of the rod 20, the cam 25 remains in the position in which the bar 31 blocks the coin chute 8. As soon as the pusher is backed off from this position to permit recharging the machine, the rod 20 is rotated in the opposite direction by the action of the spring 20' and the ends 35 and 36 of the rod 31 are withdrawn from the coin chute 8 by the reverse action of the cam 25. The machine is then restored 100

to normal and the coins deposited in the coin slot 5 will fall through the chute 8 into the control mechanism 9 to operate that mechanism to permit the discharge of an article from the machine.

5 While we have shown our invention in connection with a machine of the windlass driven type, we have done so by way of example only, as the improved coin chute and control therefor disclosed in this invention 10 can be applied to a large number of coin dispensing machines which are operated upon slightly different principles. We are not, therefore, to be limited to the specific disclosure shown.

Having thus complied with the statutes and shown and described a preferred embodiment of our invention, what we consider new and desire to have protected by 20 Letters Patent is pointed out in the appended claims.

We claim:—

1. In a dispensing machine, a coin slot, a chute communicating therewith, a coin return receptacle, said chute extending through said receptacle and having a slotted side opening into it, means controlled by the movement of a coin through said chute for dispensing articles from said machine, a lever moved by the movement of said dispensing means as it dispenses the last article from the machine, and means mechanically operated by the movement of said lever for blocking said chute to thereby cause additional coins deposited in said coin slot to fall into said receptacle.

2. In a dispensing machine, a coin slot, a chute communicating therewith, a coin return receptacle, said chute extending through said receptacle and having a slotted side opening into it, means controlled by the movement of a coin through said chute for dispensing articles from said machine, a lever moved by the movement of said dispensing means as it dispenses the last article from the machine, a cam moved by the movement of said lever, and means controlled by said cam for blocking said chute to thereby cause additional coins deposited 50 in said coin slot to fall into said receptacle.

3. In a dispensing machine, a flat plate disposed on an outside wall of said machine, said plate containing a coin slot and a return opening, a coin chute connected to said plate and communicating with said coin slot, a return receptacle attached to the back side of said plate in registration with said opening, said chute also communicating with said receptacle through a slot disposed in the side of the chute, a pair of cylindrical bushings disposed at substantially right angles to said plate and communicating with said chute, one of said bushings opening into the chute at a point above the opening of the other bushing and toward the side of the chute away from the slot in said chute, a U-shaped bar having one leg disposed in each of said bushings and ending therein short of said chute, a cam embracing the closed end of said U-bar, and means for moving said cam to cause it to move the ends of said bar legs through said bushings into and across said chute, to thereby cause a coin deposited in said coin slot to fall through said chute slot into said receptacle.

chute away from the slot in said chute, a U-shaped bar having one leg disposed in each of said bushings and ending therein short of said chute, a cam embracing the closed end of said U-bar, and means for moving said cam to cause it to move the ends of said bar legs through said bushings into and across said chute, to thereby cause a coin deposited in said coin slot to fall through said chute slot into said receptacle.

70

4. In a dispensing machine, a flat plate disposed on an outside wall of said machine, said plate containing a coin slot and a return opening, a coin chute connected to said plate and communicating with said coin slot, a return receptacle attached to the back side of said plate in registration with said opening, said chute also communicating with said receptacle through a slot disposed in the side of the chute, a pair of cylindrical bushings disposed at substantially right angles to said plate and communicating with said chute, one of said bushings opening into the chute at a point above the opening of the other bushing and toward the side of the chute away from the slot in said chute, a U-shaped bar having one leg disposed in each of said bushings and ending therein short of said chute, a second plate mounted on the inside wall of said machine and communicating with said bushings, said second plate containing a slot in which the closed end of said bar is disposed, a cam supported on said second plate and embracing the closed end of said U-bar, and means

75

80 for moving said cam to cause it to move the ends of said bar legs through said bushings into and across said chute, to thereby cause a coin deposited in said coin slot to fall through said chute slot into said receptacle.

85

90 5. In a dispensing machine, a flat plate disposed on an outside wall of said machine, said plate containing a coin slot and a return opening, a coin chute connected to said plate and communicating with said coin slot, a return receptacle attached to the back side of said plate in registration with said opening, said chute also communicating with said receptacle through a slot disposed in the side of the chute, a plurality of cylindrical bushings disposed at substantially right angles to said plate and communicating with said chute, one of said bushings opening into the chute at a point above the opening of the other bushing and toward the side of the chute away from the slot in said chute, a bar in each of said bushings, the end of which is disposed within the bushing adjacent the chute, a cam engaging said bars, and means for moving said cam to cause it to move the ends of said bars through said bushings into and across said chute, to thereby cause a coin deposited in said coin slot to fall through said chute slot into said receptacle.

95

100 6. In a dispensing machine, a flat plate disposed on an outside wall of said machine, said plate containing a coin slot and a return opening, a coin chute connected to said plate and communicating with said coin slot, a return receptacle attached to the back side of said plate in registration with said opening, said chute also communicating with said receptacle through a slot disposed in the side of the chute, a pair of cylindrical bushings disposed at substantially right angles to said plate and communicating with said chute, one of said bushings opening into the chute at a point above the opening of the other bushing and toward the side of the chute away from the slot in said chute, a bar in each of said bushings, the end of which is disposed within the bushing adjacent the chute, a cam engaging said bars, and means for moving said cam to cause it to move the ends of said bars through said bushings into and across said chute, to thereby cause a coin deposited in said coin slot to fall through said chute slot into said receptacle.

105

110

115

120

6. In a dispensing machine, the combination with a ramp for holding the articles to be dispensed from the machine, a pusher engaging the articles in said ramp and a drive mechanism for moving said pusher to thereby push an article off said ramp to dispense it from said machine, of a coin slot leading to said drive mechanism to permit a coin deposited in the machine to render the drive mechanism operative, a coin return receptacle through which said chute passes, said chute containing a slot which opens into said receptacle, and means controlled by said pusher in discharging the last article from said ramp for blocking said chute to thereby cause coins dropped into said chute to fall through said slot into said return receptacle.

7. In a dispensing machine, the combination with a ramp for holding the articles to be dispensed from the machine, a pusher engaging the articles in said ramp and a drive mechanism for moving said pusher to thereby push an article off said ramp to dispense it from said machine, of a coin slot leading to said drive mechanism to permit a coin deposited in the machine to render the drive mechanism operative, a coin return receptacle through which said chute passes, said chute containing a slot which opens into said receptacle, a plurality of bushings disposed on said chute, rods disposed in said bushings with their ends falling short of said chute, and means controlled by said pusher in discharging the last article from said ramp for moving said rods across said chute to block it and thereby cause coins deposited in said chute to fall through said slot into said return receptacle.

8. In a dispensing machine, the combination with a ramp for holding the articles to be dispensed from the machine, a pusher engaging the articles in said ramp and a drive mechanism for moving said pusher to thereby push an article off said ramp to dispense it from said machine, of a coin slot leading to said drive mechanism to permit a coin deposited in the machine to render the drive mechanism operative, a coin return receptacle through which said chute passes, said chute containing a slot which opens into said receptacle, a plurality of bushings disposed on said chute, rods disposed in said bushings with their ends falling short of said chute, a cam engaging said rods, and means operated by said pusher in discharging the last article from said ramp for moving said rods across said chute to block it and thereby cause coins deposited in said chute to fall through said slot into said return receptacle.

9. In a dispensing machine, the combination with a ramp for holding the articles to be dispensed from the machine, a pusher engaging the articles in said ramp and a

drive mechanism for moving said pusher to thereby push an article off said ramp to dispense it from said machine, of a coin slot leading to said drive mechanism to permit a coin deposited in the machine to render the drive mechanism operative, a coin return receptacle through which said chute passes, said chute containing a slot which opens into said receptacle, a plurality of bushings disposed on said chute, rods disposed in said bushings with their ends falling short of said chute, a cam engaging said rods, a rod disposed within said machine adjacent said ramp, a bell crank on said rod, a lever connecting said bell crank to said cam, and a second crank arm on the opposite end of said rod engaged and moved by said pusher as it moves the last article in the machine off the ramp to rotate the rod and thereby cause it to operate said cam to move said rods across said chute thereby blocking it and causing coins dropped into said chute to fall through said slot into the return receptacle.

In witness whereof, we hereunto subscribe our names this 17 day of Jan., 1930.

WILLIAM E. BIHL.
AXEL RAMCLAW.
